UNITED STATES PATENT OFFICE.

ANDREW WESTLAKE, OF LEADVILLE, COLORADO.

CAR-TRUCK.

SPECIFICATION forming part of Letters Patent No. 241,104, dated May 3, 1881.

Application filed February 5, 1881. (No model.)

To all whom it may concern:

Be it known that I, ANDREW WESTLAKE, of Leadville, in the county of Lake and State of Colorado, have invented certain new and useful Improvements in Car-Trucks; and I do hereby declare that the following is a full, clear, and exact description of the invention, which will enable others skilled in the art to which it appertains to make and use the same, reference being had to the accompanying drawings, which form a part of this specification.

This invention relates to that class of car-trucks in which the several wheels have independent axles; and it also relates to car-trucks provided with swinging bolsters for supporting the car.

The improvement consists in the peculiar construction of the truck-frame, and in the features of construction and combination hereinafter fully set forth, and particularly specified in the claims.

In the accompanying drawings, Figure 1 is a top view of my improved car-truck. Fig. 2 is a vertical longitudinal section on line 2 2, Fig. 1. Fig. 3 is a transverse section on line 3 3 of Fig. 1. Fig. 4 is a transverse section on line 4 4 of Fig. 1. Fig. 5 is a perspective view of the frame, which will be more clearly understood by the following description.

The upper portion of my improved car-truck, which practically constitutes the top plate, is made of iron, and is formed as follows: An outer rectangular frame, A, is made in one solid piece, whereby the usual joints heretofore incident to such frames are dispensed with, thus affording strength and cheapness of construction. An inner iron frame, B, cast in one solid piece, is firmly riveted at its ends to the under side of the ends of the outer frame, A.

The sides *b* of this inner frame are parallel with the sides *a* of the outer frame, A, the ends *b'* of said inner frame being held closely against the under surfaces of the ends *a'* of the outer frame. The bolts or rivets *b'*, which secure these two iron frames together, also secure the upper ends of braces *d* to the four corners of the inner frame, B, as will be hereinafter more specifically referred to. The upper surfaces of the two frames A B are in the same plane, to effect which it will be apparent that the ends of the frame B must be depressed adjacent to its four corners.

The braces, which are above referred to as being secured to the inner frame, consist of the upturned inclined ends *d* of the bars D D. 55 Bars E E, having similar upturned inclined ends *e*, are arranged outside of and parallel with the inner bars, D, the said ends or braces *e* being secured by bolts or rivets passing through the ends of bars F and through the four corners of the outer frame, A. The bars F are secured a portion of their length to the bars E, then upturned a portion of their length to meet the outer frame, A, and then extended along the under side of said frame, whereby 65 their ends reach the corners of frame A, where they are secured by the bolts or rivets, as aforesaid.

Inner bars, G G, are secured to the side bars of the inner frame, B. These bars G are bent 70 in the same way as the bars F, and are arranged parallel therewith, whereby said bars G furnish the inclined braces *g*.

I I represent cross-bars, which are bolted to the under side of the four bars D E F G, the 75 ends of said bars I being bent upward so as to embrace the outer edges of the outer ones of the bars, which are adapted to form braces, as aforesaid. This arrangement of frames and bars constitutes a light and exceedingly strong 80 open frame, which is in effect an iron cage.

K K indicate two vertical iron plates, which are arranged within the iron cage or frame just described and secured by bolts L passing through flanges *k*, which are formed along the 85 upper and lower edges of the plates. These bolts are also arranged to pass through and bind more firmly together the upper frames and the lower bars, D E F G, of the frame, an illustration of the manner in which said bolts 90 pass through the frames and the bars being illustrated in Figs. 1 and 2, in the former of which figures the upper ends of the bolts and the taps thereon are shown, and in the latter two bolts are indicated as binding together two 95 of said bars with the flanged plates K.

At the sides of the main structure or cage are the iron plates M, (see Fig. 4,) which said plates are formed with flanges and secured by bolts or rivets between the two vertical plates K K. 100

N N indicate the car-wheels, the axles of which are journaled in the boxes O O. The bearings for the axles are formed by plates *n*, arranged within the boxes in conjunction with

the ordinary springs n' . These boxes are fitted between the upper frames and the lower bars of the main frame or cage, and are recessed to receive the same. Bolts $P P$ alongside of said boxes hold them rigidly in place, said bolts being passed through the upper frames and the lower bars, D , of the cage. Any suitable or well-known oilers for lubricating the axles of the car-wheels can be employed.

10 R indicates a strong bolster, consisting of an elliptic spring, upon which the body of the car bears. This bolster is arranged transversely to the length of the car, and is suspended between the plates $K K$ by means of arms $r r$, which are hung upon rods S , so as to admit of a swinging movement of the said bolster. These rods or bars S have their bearings in blocks T , which are secured to the top flanges of the vertical plates K , said blocks being shown 15 in the plan view, Fig. 1. The bolster R will have any suitable socket, r' , at its top, to receive a bolt from the car-body. The lateral swing of this bolster is of especial advantage while the car is passing round a curve in the 20 road, since the friction will, in a great measure, be transferred from the outer to the inner spindles, thereby preventing hot boxes, caused by the increased rate of speed of the outer axles or spindles. It is understood that in my 25 truck I do not pass the axle from one wheel to another, but employ a separate axle for each wheel. Fig. 1 illustrates this arrangement, which, in conjunction with my swinging bolster, constitutes an important feature of the 30 invention.

35 What I claim, and desire to secure by Letters Patent, is—

1. A car-truck comprising a rectangular metal outer frame, A , made in one piece, a 40 rectangular inner metal frame, B , made in one piece, and bolted at its four corners to the under side of the end bars, a' , of said outer frame, and a series of lower longitudinal bars having their ends inclined upward to form braces, 45 which are secured to the upper rectangular frames, said parts being constructed and combined substantially in the manner shown and specified.

2. The top of a car-truck composed of the outer rectangular metal frame, A , made in one 50 piece, and the inner rectangular metal frame, B , made in one piece, and formed with its side bars depressed at their ends, the end bars, b' , of said inner frame being held along their entire length against the under side of the end bars, a' , of the 55 outer frame, and the side bars, b , of the inner frame being in the same horizontal plane as the side bars of the outer frame, the whole connected and supported by rods, bolts, and braces, substantially as described.

60 3. The combination, in a car-truck, of the rectangular outer and inner metal frames, A and B , secured together as described, with the lower longitudinal bars, $E F G$, arranged as specified, and having inclined ends secured to 65 the upper rectangular frames in the manner set forth, the transverse bars $I I$, and the bolts $P L$, substantially as shown.

4. The combination, in a car-truck, of the upper, outer, and inner rectangular metal 70 frames, A and B , with the flanged vertical plates K , the swinging bolster R , and the arms r , supporting said bolster, and hung upon rods S , as described.

5. The combination, in a car-truck, of the 75 upper, outer, and inner rectangular metal frames, A and B , secured together substantially as set forth, with the lower longitudinal bars, $E F G$, the vertical transverse plates K , provided with flanges bearing against the upper frames and lower longitudinal bars, the bolts passing through the frames, bars, and flanges, the plates M , between the ends of the transverse vertical plates, the swinging bolster R , arranged between the four plates, and 80 swinging arms supporting the bolster, substantially as shown and described.

85 In testimony that I claim the foregoing as my own I have hereto affixed my signature in presence of two witnesses.

ANDREW WESTLAKE.
